The ornamental design for a geriatric restraint, as shown and described.

DESCRIPTION

FIG. 1 is a perspective view of a geriatric restraint showing my new design as it appears on a wearer seated in a wheelchair;

FIG. 2 is a front elevational view of the restraint itself;

FIG. 3 is a right side elevational view thereof;

FIG. 4 is a rear elevational view thereof;

FIG. 5 is a top plan view thereof; and

FIG. 6 is a bottom plan view thereof.
